US0D1109003S

(12) **United States Design Patent** (10) **Patent No.:** **US D1,109,003 S**
(45) **Date of Patent:** **** Jan. 13, 2026**

(54) **NECKLACE**

(71) Applicant: **Elianotte Group Inc.**, New York, NY (US)

(72) Inventor: **Elliot Buryev**, New York, NY (US)

(73) Assignee: **Elianotte Group Inc.**, New York, NY (US)

(**) Term: **15 Years**

(21) Appl. No.: **29/860,372**

(22) Filed: **Nov. 18, 2022**

(51) **LOC (15) Cl.** **11-01**

(52) **U.S. Cl.**

USPC **D11/16**

(58) **Field of Classification Search**

USPC D11/1-3, 6, 9, 10, 12-18, 21-23

CPC .. A44C 5/00; A44C 5/02; A44C 5/022; A44C

5/025; A44C 5/027; A44C 11/00

See application file for complete search history.
